HAND-OPERATED TOOL

Thomas A. Reilly, Lakewood, Ohio, assignor to
H. & R. Products Company, Cleveland, Ohio, a
copartnership

Application November 1, 1935, Serial No. 47,893

3 Claims. (Cl. 218—1)

This invention relates to hand tools and particularly to hand tools for performing riveting, punching operations and the like.

It is an object of the invention to provide a tool of the class referred to the parts of which can be so cheaply made and so cheaply assembled that the tool can be sold to the consumer at so low a price as to make it available to the individual user who has heretofore been unable 10 to afford the price of a tool of this class.

Another object is to provide a tool of this class which can be easily and cheaply made and assembled but which will be simple and durable in operation.

15 Another object is to provide, in a tool of the class referred to, improved means for yieldably supporting a movable riveting element.

Another object is to provide generally an improved tool of the class referred to.

20 Other objects will be apparent to those skilled in the art to which my invention appertains.

My invention is fully disclosed in the following description taken in connection with the accompanying drawing, in which:

25 Fig. 1 is a side elevational view with parts broken away of a preferred embodiment of my invention;

Fig. 2 is a sectional view taken from the plane 2—2 of Fig. 1;

30 Fig. 3 is a fragmentary elevational view taken from the direction of the arrow 3 of Fig. 1;

Figs. 4 and 5 are, respectively, side elevational and end views of a tool element which I may employ instead of that illustrated in Fig. 1;

35 Fig. 6 is a view illustrating the tool of Fig. 1, performing an operation with the tool element of Figs. 4 and 5;

Fig. 7 is a fragmentary sectional view taken from the plane 7 of Fig. 1.

40 Referring to the drawing, I have shown generally at 1 a main frame comprising a base 2 having on the lower side thereof a tongue 3 and shoulders 4—4. The tongue 3 is adapted to be inserted between the jaws of a vise shown at 5 in broken lines, Fig. 3, and clamped theretwixen to support the device, the shoulders 4—4 resting upon the jaws to position the device.

A yoke 6, preferably T-form in section, having a rearwardly extending rib 7, rises from the base 2 and has a bearing 8 thereon above the forward end of the base 2. The base 2, yoke 6 and bearing 8 are preferably all formed integrally as for example in a casting. Extending entirely through the base is a bore 9 and aligned therewith is a bore 10 in the bearing 8.

In the bore 9 is preferably inserted the shank 11 of a lower riveting tool 12 having a collar 13 resting on the base when the shank 11 is in the bore 9, and provided as at 14 with an elevated portion upon which a riveting operation may be performed.

In the bore 10 is reciprocably mounted a cylindrical riveting tool 15 which may have a conical point 16 on the lower end to facilitate the riveting operation and at its upper end 17 may project upwardly beyond the bearing 8. Means to be described is provided to support the tool 15 in the bearing but permit it to be driven downwardly when struck a blow with a hammer upon the upper end 17; and as will now be apparent, by such action, a riveting operation may be performed, for example on a rivet 18 resting upon the lower riveting element 12 and in a piece of work 19, for any purpose. As illustrative of such uses is the riveting of rivets in the operation of 15 relining brakes for vehicles.

The bearing 8 has a pair of openings 20—20 at opposite sides thereof opening into the bore 10, opposite sides of the tool 15 being exteriorly exposed in the opening 20.

25 A hairpin-form or U-form spring 21, preferably made from wire, is provided straddling the rib 7 of the frame and at its free ends as shown at 22—22, Figs. 2 and 7, resiliently gripping or pinching therebetween opposite sides of the tool 15. The tool is thus supported in the bore 10. If the tool tends by gravity to slide downwardly in the bore 10, the ends 22—22 of the spring will be prevented from sliding by engagement thereof with the sides of the openings 20—20 and the frictional engagement between the ends of the spring and the tool 15 will prevent it from sliding and will support it.

30 On the other hand, however, the tool 15 may be grasped between the thumb and finger of the operator's hand and it will yieldably slide in the bore to position it above the work 19; and in any position to which it is reciprocably moved, it will remain by the friction provided for as above 35 described.

To support the rear end of the spring 21 and to position the free ends 22—22 thereof, the closed end portion 23 of the spring may be lodged in a notch 24 in the relatively thin outer edge of the rib 7.

40 The device thus far described will be seen to be relatively simple, consisting only of the frame 1 and the two tools or tool elements 12 and 15, and the spring 21; but to insure that the production cost of the device will be as small as possible, pro- 45 50 55

vision is made to facilitate assembly of the parts particularly the spring 21 with the frame. To this end, the openings 20 have a groove or grooves 25 formed in the side of the head 8 and leading 5 into the apertures, and the spring 21 is formed of sufficiently heavy wire so that when spread apart to engage the opposite sides of the tool shank 17, it will exert the necessary suspending friction and at the same time before it is assembled in work- 10 ing position and the ends of the wire are at their greatest proximity to each other, they will still be spaced apart sufficiently to easily be straddled over the edge of the rib 7. With the spring thus constructed, the ends thereof may be conveniently 15 straddled over the rib 7 at a point such as that at 26 in which the spring is diagonally disposed so that the greater part thereof may extend beyond the rib 7 and be engageable by the hand of the assembler. The ends of the spring are then 20 slid into the grooves 25 which lead them into the openings 20; then the outer end of the spring is rocked around to the notch 24 and thrust into it. The successive movements of the closed end of the spring to assemble it are indicated by the arrows 25 27 and 28, a final movement not indicated being required to finally lodge the closed end in the notch 24.

By this process of assembling, a much stronger 30 spring can be employed than otherwise because a stiff spring will cause delay in the operation of assembling it with the rest of the tool, in the absence of means to guide it to its position.

Upon removing the lower riveting element 12, the tool may be used to punch holes or to knock 35 out rivets, the latter operation being illustrated in Fig. 6 wherein a rivet 29 may be removed from a work piece 30 by a working end 31 of a tool 32. For this purpose, a tool having a cylindrical shank 33 corresponding to the shank 17 is provided and 40 the working end 31 is preferably rectangular in section as shown in Figs. 4 and 5, and to provide such a tool a piece of square section hard steel 35 may be driven into a round bore 34 in the shank 45 33. I have found that such square section knock-out tool operates in a manner superior to the usual

circular section punch or the like and that the same may be operated by a hammer blow on the end thereof as described for the tool 15.

My invention is not limited to the exact details of construction illustrated and described. 5 Changes and modifications may be made within the spirit of my invention without sacrificing its advantages and within the scope of the appended claims.

I claim:

1. In a tool of the class described, a C-form frame comprising an outwardly extending rib having an outer edge portion, and a bearing having a cylindrical bore therein, the bearing having opposite openings provided in the wall of the bore, 15 the bore receiving a cylindrical tool shank reciprocably therein, a notch in the outer edge portion of the rib, a U-shaped spring having the closed end engaged in the notch and having its legs frictionally gripping therebetween through the openings opposite sides of a tool shank in the bore.

2. In a tool of the class described, a C-form frame comprising an outwardly extending rib having an outer edge portion, and a bearing having a bore therein, the bearing having opposite openings provided in the wall of the bore, the bore receiving a tool shank reciprocably therein, a notch in the outer edge portion of the rib, a U-shaped spring having the closed end engaged in 30 the notch and having its legs frictionally gripping therebetween through the openings opposite sides of a tool shank in the bore.

3. In a tool of the class described, a C-form frame, a head having a bore therein, the head having an opening in the wall of the bore, the bore receiving a tool shank reciprocably therein, a notch in the outer convex portion of the C-form frame, a U-shaped spring having the closed end engaged in the notch and having its legs disposed 40 on opposite sides of the head and having a portion of a leg in said opening frictionally engaging, through the opening, a side of a tool shank in the bore.

THOMAS A. REILLY. 45
